11 Claims. (Cl. 333—21)

The present invention relates generally to the microwave art, and, more particularly, to a waveguide which is capable of being wound onto a drum.

Arrangements of corrugated waveguides having cross sections which are other than circular are already known. These arrangements are so constructed that a defined reference plane is provided with respect to the mechanical and electrical characteristics of the waveguide so that connection elements can be connected to the reference plane by flanges or the like. The disadvantage of such an arrangement is that a waveguide supporting structure and a transition are required and these structures, because of their cross-sectional forms are very expensive. In conventional arrangement, the necessary electrical connection is provided by suitably shaped shells which are semi-circular in cross section, or other connecting elements which surround the waveguide and are positively locked together with the housing of the arrangement. This type of construction requires a rather expensive and space-consuming mounting.

With this in mind, it is a main object of the present invention to provide a waveguide arrangement which eliminates the above-mentioned disadvantages without adversely influencing the electrical characteristics.

Another object of the invention is to provide a waveguide arrangement of the character described wherein the length of the structural elements can be decreased.

These objects and others ancillary thereto are accomplished in accordance with preferred embodiments of the invention wherein a corrugated waveguide of circular or non-circular cross section is provided with a hollow body inside the waveguide. The hollow body is fashioned so as to be outwardly resilient or have spring to it at least at its inner end and is so inserted into the waveguide that the electrical connections take place in the region of the springy portion of the hollow body. The non-resilient end of the hollow body is positively connected to the waveguide.

Additional objects and advantages of the present invention will become apparent upon consideration of the following description when taken in conjunction with the accompanying drawings in which:

FIGURE 1 is a longitudinal sectional view illustrating one embodiment of the present invention.

FIGURE 2 is a transverse sectional view taken generally along the plane defined by reference line 2—2 of FIGURE 1.

FIGURE 3 is a longitudinal sectional view similar to FIGURE 1 but illustrating another embodiment of the present invention.

FIGURE 4 is a longitudinal sectional view similar to FIGURE 3 but using a capacitive short-circuit.

With more particular reference to the drawings, FIGURES 1 and 2 illustrate an arrangement for a corrugated waveguide 1 which, for example, has an elliptical cross section. The end 2 of this waveguide portion is provided with a flange. This flange end 2 is retained in position between a reinforcing or securing flange 3 and clamping jaws 10. The flange 3 and jaws 10 are retained in position by means of bolted joints (not shown).

A hollow body 4 extends axially into the corrugated waveguide section 1. This body serves for contacting pur-

2

poses or for connections between a transmission line and the waveguide, and is connected to the flange 3 by soldering 9. This body which is provided for connecting purposes is arranged to be springy on the end which faces away from flange 3. The springiness is provided in the embodiment shown in FIGURES 1, 2 by slots 5, cut into the ends thereof.

Energy can be coupled in and out of the waveguide 1 by a coupling element which can be laterally inserted into the end of the waveguide and which may be in the form of a cross bar. In the embodiment illustrated the coupling member includes a metal rod 7 arranged parallel to the major axis of the waveguide and which is conductively or galvanically connected to the waveguide walls at its ends. The middle of rod 7 is provided with an enlargement 8 and at this point a metallic member 6 is arranged at right angles to rod 7. Metallic element 6 represents the inner conductor of a coaxial line for coupling energy into and out of the waveguide.

10 The outer conductor of such coaxial line is represented by a metal element 11 which is a semi-circle in cross section and provided with an opening 11a through which the inner conductor 6 may pass. The inner conductor 6 is supported in the opening 11a by means of an insulated disk 12. A dielectric coating 13 is provided for protecting the waveguide. Another portion which is complementary to portion 11 and which is also semicircular is section 14 which together with portion 11 annularly surrounds the waveguide.

20 The axis of rod 7 arranged at right angles to the length of the waveguide is disposed at a distance $\lambda H/4$ from the short circuit plane which is formed by the inner surface of flange 3, and where λH represents the waveguide length.

25 From FIGURE 2 it can be seen that the rod 7 is provided with recesses along the length thereof to provide a particularly large bandwidth.

30 FIGURE 3 shows a further embodiment wherein elements which are similar to those of FIGURES 1 and 2 are provided with similar reference numerals but with 40 primes added. In this arrangement the waveguide 1' is provided with a springy hollow body 4' provided with slots at its end, but the hollow body is arranged as an extension of the flange 3'. This flange 3' has a recess which is used for coupling energy into and out of the waveguide. The coupling opening 15 can, for example, have a rectangular cross section corresponding to the normal cross section for rectangular waveguides. Assuming that the waveguide 1' is provided with an elliptical cross section, this means that the hollow body 4' disposed in the corrugated waveguide at the same time serves as a transition piece for the two different waveguide cross sections. The remainder of the structure is similar to that of the previously-described embodiment, except that the energy is coupled out at the end of the waveguide section.

35 It can thus be seen that the construction provided by the present invention yields many advantages since that portion of the arrangement which is disposed outside of the waveguide can be made considerably smaller than previously since it only serves as supporting means for the element which is inserted. The conventionally used junction element is eliminated. The advantages of the present invention become particularly apparent when 45 winding the waveguide on a drum. The end of the hollow body which has spring to it and which is inserted into the waveguide for connecting purposes is suitably cut to be oblique so as to correspond to the corrugation pitch. In this case, the springy end has at least the length of one pitch of the corrugations of the waveguide. The spring effect is, for example, produced by providing elongated 50 slots in the free end of the hollow body so that the so produced spring portions are rolled outwardly in a manner which depends upon the required contact pressure. The 55

60 65 70

other end of the hollow body serves for the necessary mechanical contact with the waveguide and this contact can be provided by using attaching elements or by fitting the parts to lock together.

It has been shown that in a preferred embodiment the hollow body is provided with an end plate on the end remote from the springy end. This stop or end plate at the same time may serve as a short-circuit plate which is conventionally connected with the flanged or free end of a waveguide. The end of the waveguide is closed in this arrangement and this has great advantages during transportation because it prevents the waveguide end from becoming damaged.

Coupling energy into and out of the waveguide can be performed in the zone between the springy end and the remote end of the hollow body. For this purpose, suitable openings can be formed in order to connect the necessary coupling elements. These openings can be easily sealed for transporting the device. The coupling can be provided by inserting the coupling element laterally into the waveguide end or by connecting the coupling elements through a corresponding opening in the end plate.

If the coupling is performed through the end plate (so-called final coupling) the plastic coating which is always used in such waveguides can remain on the waveguide up to the ends thereof during mounting of the arrangement because the formation of the mechanical contact between the arrangement and the end of the waveguide requires only very little space. The stop plate itself and the supporting zone are advantageously protected against corrosion by a dielectric layer applied after mounting is accomplished.

Coupling element means is in the broader sense an element which makes possible the coupling in or coupling out of electromagnetic energy such as a pin, loop, or coupling opening.

The hollow body 4 usually consists of a springy material like bronze. The projecting strips which remain after the slots 5 are cut would be given an initial outward deformation so that they would have to be sprung inwardly in order to be inserted into the waveguide. The springiness allows a good mechanical contact of the body 4 with the waveguide. Contact will be made only with the springy end of body 4.

Instead of producing the above-mentioned electrical connection within the waveguide by mechanically connecting the hollow body, which is designed to be correspondingly flexible, the electrical contact can also be provided in an equivalent manner by a capacitive short circuit between the waveguide and the hollow body.

FIGURE 4 shows an embodiment similar to FIGURE 3 but using a capacitive short-circuit. The hollow body 4, which is springy, too, has a dielectric coating 16. The dielectric material and the thickness *b* are so chosen as to give the desired short-circuiting for the transmitted waves in the waveguide.

It will be understood that the above description of the present invention is susceptible to various modifications, changes, and adaptation, and the same are intended to be comprehended within the meaning and range of equivalents of the appended claims.

What is claimed is:

1. A waveguide arrangement, comprising, in combination:

a corrugated waveguide capable of being wound upon a drum, the corrugations having a certain pitch; and a hollow body disposed in one end of the waveguide and having only its inward portion outwardly springy, said body being inserted into the waveguide

so that electrical connections can be provided in the springy portion of the hollow body, and the other end of the hollow body being firmly connected with the waveguide, the springy end of the hollow body being oblique with respect to the longitudinal axis of the waveguide so as to correspond to the corrugation pitch of the waveguide and the springy end having at least the length of one pitch of the corrugation.

2. An arrangement as defined in claim 1 wherein said other end of the hollow body is an end plate for the waveguide.

3. A waveguide arrangement, comprising, in combination:

a flexible waveguide capable of being wound upon a drum; a hollow body disposed in one end of the waveguide and having only its inward portion outwardly springy, said body being inserted into the waveguide so that the electrical connections can be provided in the springy portion of the hollow body; and means for firmly connecting the other end of the hollow body with the waveguide.

4. An arrangement as defined in claim 3 wherein an electrical contact is provided between one end of the hollow body and the waveguide by means of a capacitive short circuit.

5. An arrangement as defined in claim 3 comprising connecting means for coupling energy into and out of the waveguide and connected in the region between the springy portion and the other end of the hollow body.

6. An arrangement as defined in claim 5 wherein said connecting means includes a coupling element inserted laterally into the end of the waveguide.

7. An arrangement as defined in claim 5 wherein said other end of the hollow body is an end plate for the waveguide.

8. An arrangement as defined in claim 7 wherein the connecting means includes an element which passes through the stop plate.

9. An arrangement as defined in claim 5 comprising an end plate on said waveguide, said other end of the hollow body being connected to said end plate.

10. A waveguide arrangement, comprising, in combination:

a flexible waveguide capable of being wound upon a drum; and a hollow body disposed in an end of the waveguide and having only its inward portion outwardly springy, said body being inserted into the waveguide so that the electrical connections can be provided in the springy portion of the hollow body, and the other end of the hollow body being firmly connected with the waveguide.

11. An arrangement of a waveguide capable of being wound on a drum, comprising, in combination:

a waveguide tube which is flexible so as to be capable of being wound on a drum; and a hollow body of suitable cross section disposed in said tube, said hollow body being arranged so as to have spring in an outward direction and being inserted into the waveguide tube so that electrical connecting takes place in the vicinity of the springy portion of the hollow body, the non-springy end of the hollow body being positively connected with the waveguide.
